UNITED STATES PATENT OFFICE.

JOHN J. LONERGAN AND ALBERT C. CALKINS, OF LOS ANGELES, CALIFORNIA.

ASSAYER'S FURNACE.

SPECIFICATION forming part of Letters Patent No. 608,883, dated August 9, 1898.

Application filed January 12, 1898. Serial No. 666,436. (No model.)

To all whom it may concern:

Be it known that we, JOHN J. LONERGAN and ALBERT C. CALKINS, of Los Angeles, in the county of Los Angeles and State of California, have invented a new and useful Improvement in Assayers' Furnaces, of which the following is a specification.

As is well known to those skilled in the use of muffle and allied furnaces, more especially those in which a highly-volatile hydrocarbon, such as gasolene, is employed as fuel, the oxidation of the charges is defective, so that cupellation is practically impossible in a large portion of the muffle and is effected slowly and imperfectly even in the remaining portion. To remove this objection, we provide an attachment for the class of furnaces referred to whereby oxidation is promoted to such a degree that cupellation is effected rapidly and completely in all parts of the muffle.

Our invention is embodied in the construction and combination of parts, as hereinafter described.

In the accompanying drawings, Figure 1 is a perspective view of a muffle-furnace provided with our improvement. Fig. 2 is a longitudinal vertical section of the same.

The body of the furnace *a* and the muffle *b* therein are shown arranged and the former provided with a flue *c* in a well-known manner. Instead of the muffle *b* being closed at its inner or rear end it is provided with an opening 1, that communicates with a horizontal passage 2 in the adjacent end wall of the furnace *a*, and said wall is also constructed with a boss or tubular extension 3, as shown. Our tubular oxidizing attachment is shown connecting such boss 3 with the furnace-flue *c*—that is to say, the same consists of an angular sheet-metal pipe or tube 4, one end of which engages the furnace-boss or extension 3 and the other or upper end is permanently attached to the main flue *c*. Such

pipe or tube 4 is also provided with a damper 5, which may be adjusted as required.

The heat in the main flue *c* creates by induction a draft of air in the attachment 4 and through the muffle *b*. The increased quantity of air thus drawn into the latter furnishes a plentiful supply of oxygen, so that the cupel charges are rapidly and completely oxidized in all parts of the muffle *b*. In this operation the unconsumed gases and fumes pass through the attachment into the main flue. Thus by this simple and inexpensive attachment the work of the furnace is greatly promoted and rendered practically uniform and complete.

What we claim is—

1. The improved assaying-furnace, adapted for burning gasolene or other hydrocarbon, the same comprising the body or casing *a*, having the rear horizontal passage 2, the muffle having a rear opening registering with such passage, the rear tubular extension or boss 3, the main flue attached to top of the furnace, and the oxidizing attachment, consisting of the exterior pipe 4, connecting the aforesaid boss and main flue, and provided with a damper, as shown and described.

2. The improved assaying-furnace, comprising the body *a* having the rear passage 2, the muffle arranged with its inner end provided with an opening and separated from the rear wall of said body, save where the passage and opening coincide, the main flue, and the oxidizing attachment consisting of an exterior pipe which connects the aforesaid passage and main flue, as shown and described.

JOHN J. LONERGAN.
ALBERT C. CALKINS.
